UNITED STATES PATENT OFFICE.

ROBERT N. BRUCE AND JAMES M. BROWN, OF SPERRYVILLE, VIRGINIA.

SEEDING-MACHINE.

SPECIFICATION forming part of Letters Patent No. 242,505, dated June 7, 1881.

Application filed April 4, 1881. (Model.)

To all whom it may concern:

Be it known that we, ROBERT N. BRUCE and JAMES M. BROWN, both of Sperryville, in the county of Rappahannock and State of Virginia, have invented certain new and useful Improvements in Seeding-Machines; and we do hereby declare that the following is a full, clear, and exact description of the invention, which will enable others skilled in the art to which it appertains to make and use the same, reference being had to the accompanying drawings, which form a part of this specification, and in which—

Figure 1 is a top-plan view. Fig. 2 is a rear view. Fig. 3 is a side view. Fig. 4 is a vertical longitudinal sectional view. Fig. 5 is a vertical cross-section.

Corresponding parts in the several figures are denoted by like letters of reference.

This invention relates to a combined seed-sower and fertilizer-distributer; and it consists in certain improvements in the construction of the same, which will be hereinafter fully described, and particularly pointed out in the claims.

In the drawings hereto annexed, A represents the frame of the machine, which is mounted upon an axle, B, one of the wheels of which, C, is fixed, in order to cause the axle to revolve in its bearings.

D is the hopper, which is provided with a partition, E, arranged close to its front side, so as to form a passage, F, at the upper end of which is formed a small secondary hopper or seed-box, G, the bottom of which, H, is provided with a series of perforations, I, opening into the passage F. J is the seed-slide, which is provided with perforations K, and which reciprocates upon the bottom H, it being provided with an arm, L, which extends through a slot, M, in the side of the hopper, and to which operating mechanism (to be hereinafter described) is attached.

N is a transverse shaft, journaled in the sides of the hopper D, and carrying a longitudinally grooved or fluted cylinder, O, fitting closely against the lower edges of the body of said hopper. Any desired number of the grooves P in cylinder O may be closed by means of strips Q, fitted nicely therein, and secured by wood-screws or in any other suit-

able manner. The shaft N is provided with a gear-wheel, R, fixed at one of its ends and engaging a similar wheel, S, secured upon the axle B, which thus serves to rotate shaft N when the machine is operated.

S² is a sliding agitator, provided with wings or stirrers T, and fitted transversely just above the fluted roller O in hopper D, through the sides of which the ends of said rod project, as shown. The inner side of the gear-wheel R and the inner side of a disk, U, fixed at the other end of shaft N, are provided on diametrically opposite sides with beveled projections V, which, as the shaft N rotates, strike the projecting ends of the rod S², thus forcing the latter alternately in opposite directions and serving to stir the contents of hopper D.

The lower edge of the rear side of hopper D is constructed of a series of doors, W, secured by spring-hinges X, so as to be capable of opening in an outward direction. Any lumps or hard pieces which may be found in the fertilizing material contained in hopper D, and which, when fed by the fluted cylinder O, might tend to obstruct the working of the machine, will, by this arrangement, simply force one of the doors W open sufficiently to escape.

Y is a cleaner or scraper secured to the front side of the hopper D by means of suitably-constructed springs Z. The function of this scraper is to bear against the face of cylinder O and remove from the grooves of the latter any obstructions which, by reason of moisture or otherwise, might clog or accumulate therein.

A' is a trough or sifter, suspended from the under side of the hopper by means of hooked rods B', and connected, by arms C', with cranks D', formed upon the shaft E', which is journaled in the downward-projecting sides of the hopper, as shown. Shaft E' is provided at one end with a gear-wheel, F', engaging the gear-wheel S upon axle B, thus causing the sifter A' to be shaken or reciprocated by the revolution of the axle.

Upon the outer side or face of gear-wheel F' is pivoted a connecting-rod or pitman, G', the upper end of which is hooked or adjusted in one of a series of perforations, H', in the lower or horizontal arm of a bell-crank lever, I', pivoted in a bracket, J', extending laterally

from the side of hopper D. The upper or vertical arm of the said bell-crank lever is adjusted in a perforation, K', in the projecting arm L of the seed-slide, which is thus reciprocated by means of the said bell-crank lever, which latter is operated by the revolving shaft E'.

The sides L' M' of hopper D project downwardly, as shown, and are provided or formed with shoes or brackets, by means of which it is supported upon the frame, the sides of the latter being provided with pins L² M², of which those under side L' are straight or vertical, while those under side M' slant or incline in a forward direction.

Corresponding openings, N', are provided in the sides L' M'.

A crank-lever, O', pivoted to the side of the frame has its short arm pivoted to the side M', and its long arm extending forward and adjustable in one of several notches, P', in an upright, Q', secured to the side of the frame. By this arrangement, when the front end of lever O' is lowered the side M' is raised and slides forward upon the inclined pins M², thus throwing the gear-wheels R F', which are arranged on this side, out of gear with the wheel S upon the axle, thus stopping the operation of the machine.

From the foregoing description, taken in connection with the drawings hereto annexed, the operation and advantages of this invention will be readily understood.

The seed fed by the reciprocating seed-slide drops through the passage F down upon the cylinder O, which receives it in one of its grooves. This in passing under hopper D is filled with the fertilizing substance contained in the latter, and the whole is discharged into the sifter A', by which it is thoroughly scattered. This sifter, however, may be omitted when desired.

The quantity of seed sown may be regulated by the number and size of the openings in bottom H and in the seed-slide, and these should be so disposed that when the machine is at rest and out of gear, and the cranks of shaft E' drop down to their lowest position, the seed-openings in bottom H shall be closed by the seed-slide, thus preventing the waste of seed.

The quantity of fertilizing material to be dropped may be determined by covering one or

more of the grooves in cylinder O with the strips Q.

This machine will work when backed as well as when drawn forward, and may thus be backed up in corners, &c., not otherwise accessible. 55

The construction is simple, cheap, and durable.

Having thus described our invention, we claim and desire to secure by Letters Patent of the United States— 60

1. In a seeding and fertilizer-dropping machine, the combination of the seed-bar J, located in the seed-hopper G, with its discharge-spout forming a subdivision of the main hopper D, crank-arm H', working in the eye or support J', rod G', pinion F', gearing with a pinion, S, upon the driving-shaft, and having a crank-shaft, E' D', and suspended screen or sifter A', connected by rod C' to the aforesaid crank-shaft, substantially as and for the purpose set 70 forth.

2. In a seeding and fertilizer-dropping machine, the combination of the seed-bar J, seed-hopper G, main hopper D, crank-arm H', working in the eye or support J', rod G', pinion F', 75 gearing with a pinion, S, upon the driving-wheel shaft and having a crank-shaft, E' D', connected by a rod, C', to the suspended sifter A', and stirrer S² T, vibrated alternately by the cams V V on opposite sides of the frame, 80 substantially as and for the purpose set forth.

3. The combination, with the frame A, having axle B, provided with gear-wheel S, crank-lever O', vertical studs L², and inclined studs M², of the hopper D, having shafts N E', carrying gear-wheels R F', and having downward-projecting sides L' M', provided, respectively, with straight and inclined openings adjusted upon the pins or studs L² M², the short arm of lever O' being pivoted to the side M' of the 90 hopper, all as and for the purpose herein shown and specified.

In testimony that we claim the foregoing as our own we have hereunto affixed our signatures in presence of two witnesses.
